UNITED STATES PATENT OFFICE.

WILLIAM FRANCIS DUGINS, OF KEW, VICTORIA, AUSTRALIA.

COMBINED TOBACCO-BOX COVER AND CUTTER.

No. 830,140.

Specification of Letters Patent.

Patented Sept. 4, 1906.

Application filed May 10, 1906. Serial No. 316,061.

To all whom it may concern:

Be it known that I, WILLIAM FRANCIS DUGINS, a subject of the King of Great Britain, residing at Peel street, Kew, in the State 5 of Victoria, Australia, have invented certain new and useful Improvements in a Combined Tobacco-Box Cover and Cutter; and I do declare the following to be a full, clear, and exact description of the invention, such as will 10 enable others skilled in the art to which it appertains to make and use the same.

This invention has been devised to provide a combination lid for a tobacco-box and a cutter for tobacco, and is designed to obviate the 15 necessity of carrying a separate knife for cutting such tobacco, as is the practice at present.

In order that my invention may be the more easily understood, reference may be 20 made to the accompanying drawings, in which—

Figure 1 shows the front elevation of my tobacco-box cover and cutter, the box being in section for clearness of view. Fig. 2 is a plan 25 of Fig. 1; Fig. 3, a side elevation taken at line 1 2 on Fig. 2, the box being also in section, showing the lid in its open or cutting position. Fig. 4 is a similar view to Fig. 3, but showing the lid in its closed or non-cutting position, 30 while Fig. 5 is a side view of the lid-cutter, drawn to a large scale, to the more easily illustrate some of the parts embodied in the previous sketches.

In the drawings, A represents a tobacco- 35 box which may be rectangular in its construction, as shown, and has an open top, in which is placed the parts embodying my invention.

B is a curved lid of thin metal plate centered upon a spindle C. This spindle 40 projects through each of the sides of the box A, so that the lid B can partly revolve upon it.

D is the termination of the top of the plate B and consists of a sharpened cutting edge running parallel almost the whole length of the 45 top of the box—that is to say, terminating at each end in the side disks E of the lid B. Placed immediately under the said cutting edge D is a free revolving roller F, mounted upon an internal bearing rod or shaft F', the 50 latter being secured, preferably by soldering, at each end F² into the cheek E.

G is a small ridge-piece placed in the middle at the top of the lid B and is set somewhat hook-shaped in section, so that when it is 55 pushed back onto the top of the box A at A' it will stop the lid B from moving any farther

backward. Small bulging points H project outwardly from the side of each cheek-disk E, their object being to cause friction against the inner face of the box at those parts and 60 prevent the lid B from automatically opening or closing, the pressure being so adjusted that a fair push is required with the forefinger and thumb upon the lid before it will either open or close. 65

In operation the person desiring to cut tobacco opens with his forefinger and thumb the lid B until the stopper-plate or ridge-piece G meets the edge A' and stops the further progress of the said lid B. He then takes hold 70 in his left hand of the box A, with the cutting edge pointing to his left-hand side. With his right hand he grasps the fig or cake of tobacco and with pressure draws it across the roller F and the knife-edge D, using his right 75 thumb to press against the back of the box A under the part A', so as to act as a fulcrum to his hand. The tobacco when drawn with pressure over the edge D will be cut in fine strips or shavings and will pass down between the roller F and said cutting edge D into the box A. When the latter has been 80 sufficiently supplied with the cut tobacco, the forefinger and thumb are applied under the ridge-piece D at A' and the lid B partly 85 revolved over, so that the top of the box is closed. The pressure of the frictional excrescences H will hold the lid from coming open while in the user's pocket. In some cases I may employ some simple little clip or catch 90 in lieu of or in addition to the device at H in order to lock the lid the better in position should same be required.

Having thus described my invention, what I claim, and desire to secure by Letters Patent, is—

1. In combination a tobacco-box, a curved tobacco-box cover the closing edge of which is sharpened and under which said edge a roller is placed so arranged that when a plug 100 of tobacco is drawn across the said roller and cutting edge the tobacco is cut and falls into the box beneath substantially as and for the purposes set forth.

2. A tobacco-box having a combined tobacco-box cover and cutter comprising a curved lid running the whole length of the top of the box and pivoted at each end in a bearing set in the cheeks of the said box, the top edge of said lid being sharpened and under which a roller is set and the top of the lid being provided with a thumb-nail ridge- 105 110

piece to form a stopper against undue back-
ing of said lid substantially as and for the
purposes set forth.

3. In combination a tobacco-box as A, a
5 curved lid as B centered at each end in bear-
ings as C, said lid being provided with a cut-
ting edge as D, roller as F, and bulging points
as H to cause friction with the inner face of
the said box A, and a stopper-plate as G, sub-

stantially as set forth and as illustrated in 10
the accompanying drawings.

In testimony whereof I have signed my
name to this specification in the presence of
two subscribing witnesses.

WILLIAM FRANCIS DUGINS.
